UNITED STATES PATENT OFFICE

173,159

MUSICAL DEVICE WITH ROTATABLE STRIKERS

John Joslyn, New York, N. Y.

Application February 24, 1954, Serial No. 29,197

Term of patent 14 years

(Cl. D56—1)

To all whom it may concern:

Be it known that I, John Joslyn, a citizen of the United States, residing at New York city, in the county of New York and State of New York, have invented a new, original, and ornamental Design for a Musical Device With Rotatable Strikers, of which the following is a specification, reference being had to the accompanying drawing, forming part thereof.

In the drawing

Fig. 1 is a side elevational view of a musical device with rotatable strikers, showing my new design;

Figure 2 is a top plan view;

Figure 3 is a side elevational view as turned 90° from Figure 1; and

Figure 4 is a view as taken along the line 4—4 of Figure 1.

I claim:

The ornamental design for a musical device with rotatable strikers, substantially as shown.
